UNITED STATES PATENT OFFICE

NELS H. NELSON, OF DES MOINES, IOWA

WINDOW-AWNING CONSTRUCTION

Application filed June 8, 1925. Serial No. 35,775.

The object of my invention is to provide a window awning construction of simple and durable construction and comparatively easy to manufacture.

More particularly, my invention relates to a track or guide in which a U-frame to which the awning canvas is fixed may travel a predetermined distance and thereafter the U-frame will swing outwardly and downwardly as though pivoted to the track.

Still a further object is to provide a casing for the awning when it is in rolled-up position and to provide a connection between the canvas proper and the U-frame, so that the connection will serve as a closure member for completely enclosing the casing in which the canvas is received and thereby preventing any portion of the canvas being exposed to outside atmospheric conditions.

Still a further object is to provide a substantially grooved track in which is slidably mounted ball members formed on the free ends of the U-frame, which ball members become temporarily anchored in the lower ends 25 of the track, whereby the frame may be swung outwardly and downwardly and retained in its downward position.

With these and other objects in view, my invention consists in the construction, arrangement and combination of the various parts of my construction, whereby the objects contemplated are attained, as hereinafter more fully set forth pointed out in my claims, and illustrated in the accompanying drawings, in which:

Figure 1 is a front plan view of a window with my window awning shown thereon partly withdrawn.

Figure 2 is a side view of the awning showing it in partly withdrawn position.

Figure 3 is an enlarged, sectional view of the track in which the U-frame of the awning travels, one position being shown in dotted lines.

Figure 4 is a sectional view through the casing in which the awning is mounted showing the connection between one end of the canvas and the cross member of the U-frame; and

Figure 5 is a detailed, sectional view taken

substantially at the joint between two portions of the track shown in Figure 3 of the drawings.

In the accompanying drawings, I have used the reference numeral 10 to indicate generally a window frame or casing, which is provided with the ordinary window sashes 11.

Secured to the upper cross member of the frame 10 is a casing 12 having an opening formed in its bottom near the forward wall. The edge of the material of the casing 12 at the opening referred to by the reference numeral 13 is bent back and doubled over, so as to provide a smooth edge over which the canvas of the awning, which will hereinafter be described, may travel.

Mounted within the casing 12 in any suitable manner is a spring-actuated roller 14. I have not shown the spring of the roller 14 and any suitable type of spring actuated roller may be employed.

Mounted upon the roller 14 is a strip of canvas 15, which is adapted to be rolled around the roller, as clearly shown in Figure 4 of the drawings.

On each side of the frame 10 is a track 16, which is formed of a pair of similar sections of sheet metal, which are formed so as to be substantially circular in cross section, and to have a pair of out-turned flanges 17. The flanges 17 tend to reinforce and strengthen the track 16.

The two parts of the track 16 are connected together by any suitable fitting 18, which is screwed or otherwise fastened to the frame 10.

The upper end of the track 16 is secured to the casing 10 by a screw 19 passing through an opening in the track and entering the frame 10.

The lower end of the track 16 below the fitting 18 is inclined slightly outwardly.

A fitting 20 having a substantially U-shaped opening 21 therein coacts with the lower end of the track 16 and forms a continuous passageway.

The fitting 20 is secured to the frame 10 by screws or the like. It is formed with a yoke-shaped socket portion 29 which engages the lower end of the track 16.

Slidably mounted relative to the track 16 is a U-shaped frame 22, which has a pair of ball members 23 fitted in its free ends.

The ball members are designed to travel in the tracks 16. The space between the two flanges of the tracks 16 is sufficient to permit the U-frame to extend therethrough, although the ball members 23 are of greater size than the distance between the two flanges 17 and therefore the ball members are retained within the tracks 16.

The rearwardly and upwardly directed terminal portions or sockets of the fittings 20 are of considerable length in order to retain the ball members 23 therein and prevent accidental displacement such as might occur, due to the action of the wind. For this purpose, the ball members 23 are of elongated form, being substantially semi-spherical at their terminal portions and of greater diameter than the end portions of the U-shaped frame 22 to which they are attached. The inner end portions of the ball members 23 are substantially frusto-conical and taper gradually toward the frame arms. The depth of the socket openings in the fittings 20 corresponds substantially with the length of the ball members 23.

When draft is applied to the U-shaped frame 22 by means of the member 27, the ball members 23 travel downwardly in the channeled guides 16 and when they reach the lower ends of said guides, they move rearwardly and upwardly into the socket openings of the fittings 20 and are effectively retained therein so long as tension is maintained on the draft member 27 for holding the awning in any of its adjusted positions. When draft on the member 27 is released, the action of the spring roller 14 serves to pull upwardly on the awning 15 and on the outer end of the U-shaped frame 22. Such pull causes the ball members 23 to slip past the lower ends of the sockets in the fittings 20, the tapered portions of the ball members 45 sliding around the point which separates the sockets from the guide tracks. Thereafter, the ball members travel upwardly in the channeled members to the position shown by 50 solid lines in Figure 3.

The awning or canvas 15 is secured to the cross member 24 of the U-frame by the use of a metal clip 25, which is bent to substantially U-shape and extends around the cross member 24 and has its ends turned inwardly towards each other to receive therebetween the free edge of the canvas 15.

The connecting member 24 of the U-frame 22 is permitted to move relative to the clip 25. The canvas 15 is connected to the clip 25 by suitable rivets or the like 26, which extend through two sides of the clip 25 and also through the canvas which is received therebetween.

The clip 25 is designed to extend up into

the casing 12 and fill the opening 13 thus sealing the entire casing 12 and protecting the canvas 15.

The metal clip 25 around the U-frame 22 gives me a connection which permits free and easy movement of the U-frame, and at the same time serves as a closing member for the opening in the casing 12.

Any suitable control may be used for movement of the awning from one position to another, and I have shown in the drawings a chain 27, which extends around a suitable pulley or the like 28 mounted on the sill of the frame 10.

The roller 14, which is spring-actuated, tends to hold the awning in its closed or rolled up position, and when in this position, the parts are as shown in Figure 3 of the drawings.

When the chain 27 is pulled downwardly, the first thing that happens is to cause the awning or canvas 15 together with the U-frame to be pulled directly downwardly until the lower ends of the U-frame or balls 23 are engaged with the passageway 21 in the fitting 20.

The position of the parts just described is clearly illustrated in Figure 2 of the drawings.

Further pulling on the chain 27 will cause the U-frame to swing outwardly and thereafter to swing downwardly, so that the awning may really be substantially flat against the window when completely drawn down.

In most cases, however, the awning is used as an ordinary awning, that is with the canvas portion inclined outwardly, as shown in Figure 2 of the drawings.

The awning when serving as a curtain or the like is completely drawn down, and the U-frame assumes the position shown in dotted lines in Figure 2.

The ball members 23, traveling in the passageway 21 and the fitting 20, pass around a shoulder formed in the fitting 20, which gives to the U-frame the desired movement, that is engagement of the balls 23 around the shoulder in the fitting 20 causes the inner ends of the U-shaped member to remain positive.

When the inner ends of the U-shaped member 22 are in engagement with the fitting 20, then the parts move as though the inner end of the U-member were directly pivoted thereto.

The metal clip 25 extending around the connecting member 24 of the U-frame tends to strengthen the U-frame and prevent any possible bending or sagging at the cross member 24. The metal clip 25 also serves to prevent the awning or canvas, which otherwise would extend around the connecting member 24 from wearing out.

Some changes may be made in the arrangement and construction of the various parts of my device, without departing from the

real spirit and purpose of my invention, and it is my intention to cover by my claims, any modified forms of structure or use of mechanical equivalents, which may be included within their scope.

5 I claim as my invention:

1. In a window awning structure including a frame member having a ball member on one end and a canvas fixed to said frame member and arranged to be wound and unwound; a guide structure for said frame member comprising a longitudinally channeled member in which said ball member is arranged for travel, and an upwardly directed socket at the lower end of said channeled member adapted to receive said ball member to prevent its upward sliding movement and to permit pivotal movement of said frame member.
- 10 2. In a window awning structure including a frame member having a ball member on one end and a canvas fixed to said frame member and arranged to be wound and unwound; a guide structure for said frame member comprising a longitudinally channeled member in which said ball member is arranged for travel, and a member at the lower end of said channeled member formed with a laterally and upwardly directed continuation of the channel thereof to provide a socket for receiving said ball member, whereby to prevent upward sliding movement of said ball member and to permit pivotal movement of said frame member.
- 15 3. In a window awning structure including a U-shaped frame and a canvas fixed to said frame and arranged to be wound and unwound; a guide structure for said frame comprising a pair of longitudinally channeled members into which the free ends of the frame arms are extended for sliding movement, an elongated ball mounted on the free end of each frame arm and received in one of said channeled members, each of said balls being semi-spherical at its end and tapering toward the end of said frame, and a rearwardly and upwardly directed socket at the lower end of each channeled member, said sockets being of greater length than the diameter of the said balls and adapted to receive said balls to hold them against upward sliding movement and to permit pivotal movement of the frame.
- 20 4. In a window awning structure including a U-shaped frame and a canvas fixed to said frame and arranged to be wound and unwound; a guide structure for said frame comprising a pair of longitudinally channeled members into which the free ends of the frame arms are extended for sliding movement, a ball on the free end of each frame arm for travel in one of said channeled members, each ball having a semi-spherical terminal portion of greater diameter than the frame arm and an elongated frusto-conical portion tapering toward the frame arm, and a rearwardly and upwardly directed socket at the lower end of each channeled member, said sockets being of a length corresponding substantially with the length of said balls, whereby the balls are retained therein against accidental displacement so long as downward draft is applied to the outer portion of the frame and are permitted to move past the lower points of the sockets and into the channeled members when such draft is released.
